UNITED STATES PATENT OFFICE.

JOHN BURGE, OF WESTFIELD, MASSACHUSETTS.

AUTOMATIC DAMPER-REGULATOR.

SPECIFICATION forming part of Letters Patent No. 315,904, dated April 14, 1885.

Application filed December 29, 1884. (No model.)

To all whom it may concern:

Be it known that I, JOHN BURGE, a citizen of the United States, residing at Westfield, in the county of Hampden and State of Massachusetts, have invented certain new and useful 5 Improvements in Automatic Damper-Regulators; and I do hereby declare the following to be a full, clear, and exact description of the invention, such as will enable others skilled in 10 the art to which it appertains to make and use the same.

My invention relates to certain improvements in automatic damper-regulators which can be set to open or close a damper or other 15 similar device at any desired time.

It consists of certain novel construction and arrangement of the various parts, all of which I will now proceed to point out and describe, reference being had to the accompanying drawings, in which—

Figure 1 is a side elevation. Fig. 2 is a detail view of some of the parts.

Referring to said drawings, A is a plate secured to a suitable vertical frame or wall. B is a lever pivoted at one end to the lower part 25 of the plate A, and is connected by a chain, a, or othersuitable means, with the damper, which may be set to open or close by the falling of said lever B. b is a projection on the plate A, and 30 has the incline surface b', on which the lever B rests. C is a stop which limits the downward movement of the lever. D is a latch pivoted to the upper part of the plate A, and is provided with its lower end with the wedge shaped 35 point d. Said point d coming between the lever B and plate A as the latch falls forces said lever off the incline b' and causes it to drop to the position shown in dotted lines. E is a lever-arm pivoted at one end to the frame or 40 wall at a point above the plate A, and having its free end e bent in toward the wall. e' is a rod connecting the lever-arm with the latch E. F is a rotating disk having the notch f. On 45 the periphery of the disk the end e of the lever-arm E rests. Said disk is so arranged that

when set in motion the notch f will come directly under the end e at any desired time. To accomplish this the disk is connected with the mechanism of the clock G by any of the well-known devices used for such purpose. It 50 may be made a part of and attached to the back of the clock, as shown in the drawings.

The operation of my device is as follows: The lever B is placed upon the incline surface b' of the projection b, and is connected by any 55 suitable device with a damper or valve which is set to open or close when the lever falls from the incline. The end e of the arm E rests upon the periphery of the disk F and holds the lever B on the incline surface b' by means of 60 the connecting-rod e'. The disk F is then set to rotate, so that the notch f will come directly under the end e of the arm E at any desired time. When the notch f comes under the end 65 of the arm, it drops into said notch, as shown in dotted lines, and causes the latch D to fall. The wedge-shaped point d coming between the 70 lever B and plate A causes said lever B to drop to position shown in dotted lines, and thus operates the damper or valve.

Having thus fully described my invention, I claim as new and desire to secure by Letters Patent—

1. The plate A, having the projection b, and lever B, pivoted to said plate A, in combination 75 with the latch D, having the wedge shaped point d, substantially as shown and described.
2. The disk F, adapted to be rotated and having the notch f, the arm E, connecting-rod e', and latch D, having wedge-shaped point d, 80 in combination with lever B and projection b, all arranged and operating substantially as shown and described.

In testimony whereof I affix my signature in presence of two witnesses.

JOHN BURGE.
